UNITED STATES PATENT OFFICE

HENRY A. THOMSON, OF LANSDOWNE, PENNSYLVANIA, ASSIGNOR TO GLOBE TICKET COMPANY, OF PHILADELPHIA, PENNSYLVANIA, A CORPORATION OF PENNSYLVANIA

TICKET PRINTING AND ISSUING MACHINE

Application filed February 5, 1931. Serial No. 513,505.

This invention relates to a motor driven printing machine of the type in which portions of a strip or web are printed to form tickets, the printing being effected by means 5 of a single rotary type cylinder cooperating with means whereby the form to be printed may be selected at the will of the operator. The improvements forming the subject matter of this application are particularly 10 adapted to the type of machine described in certain applications filed by Christopher Frederick Webb, Serial Numbers 260,268, 301,843 and 480,990, filed, respectively, March 9, 1928, August 24, 1928 and September 10, 15 1930. It will be noted from the following description that the general operation is quite similar to the operations of the machines of these applications, and, in fact, the present machine embodies in identical 20 form many of the features of these machines.

It is one object of the present invention to provide a machine of this general character with improved means whereby but one ticket is issued upon a single depression of 25 a key even though the key be maintained depressed following the completion of a ticket issuing cycle. One specific feature auxiliary to the accomplishment of this object is an improved arrangement for insuring 30 the completion of any cycle of operation which is initiated.

Another object of the invention relates to an improvement in the strip feeding means whereby positive feed is obtained 35 without sacrifice of ease of insertion of a new strip. An associated object is the provision of improved strip severing means having actuating means in common with the feeding means.

40 A further object is the provision of a simple driving arrangement which is positive and still so simple that compactness is obtained.

It is also an object of the invention to 45 provide an arrangement whereby inking of all the operating type surfaces takes place prior to their use during any cycle.

Still another object concerns an arrangement whereby the type cylinder may be rotated freely of the other mechanisms to

facilitate the replacement or cleansing of the type. This arrangement has associated with it means whereby a numbering head may be rendered inactive so as not to register such idle rotations. 55

An additional object of the invention relates to an improved switch device whereby the motor may be spun without having the machine perform a complete cycle of operation, this being particularly advantageous in effecting discharge of a ticket in case it is not properly discharged in the normal operating cycle, or in properly distributing ink upon the inking roller after a period of rest. In the present machine, it 60 may be pointed out, the inker is driven directly by the motor and not through those parts which have only cyclical operation. 65

Other objects of the invention, relating particularly to details of construction will 70 be apparent when the following description is read in conjunction with the accompanying drawings, in which:

Fig. 1 is a vertical section of the machine taken approximately on the plane indicated 75 in Fig. 2, the parts being viewed in the direction of the arrows 1-1;

Fig. 2 is a generally vertical section of the machine illustrating certain of the interior parts in front elevation or partially 80 broken away, certain parts being omitted for clearness;

Fig. 3 is a vertical section of the machine taken approximately on the same plane as Fig. 1, the parts being viewed oppositely in 85 the direction of the arrows 3-3;

Fig. 4 is a generally horizontal section taken on the surface indicated by the face 4-4 in Fig. 1, various parts being omitted for clearness; 90

Fig. 5 is a front elevation of the mechanism taken interiorly of the face plate of the casing, parts being broken away;

Fig. 6 is a side elevation of the type cylinder, shaft and associated parts; 95

Fig. 7 is a perspective view of details of construction; and

Fig. 8 is a sectional view showing details of the switch arrangement.

The operating parts of the mechanism are 100

enclosed within a casing designated as a unit by 2, the casing being provided with a removable top plate 4 and an interior front plate 6. This casing is adapted to ⁵ mount a suitable magazine containing a ticket strip supply of the usual roll or folded type, the end of the strip passing upwardly to the mechanism as indicated at S in Fig. 1. It will be obvious that the form of the ¹⁰ particular casing and its relationship to the supply are capable of wide variation and, so far as the operation of the mechanism is concerned, are immaterial.

A motor 8 furnishes the power necessary ¹⁵ for the operation of the mechanism through suitable reduction gearing 10 which drives a gear 12. The gear 12 in turn drives the large gear 14 carrying the ratchet wheel 16, the combination being journalled upon the ²⁰ main shaft 17 having suitable bearings in the side plates of the frame. The nose 18 of a pawl 20, pivoted to a member 22 fixed to the shaft 17 and urged by a spring 24 in a clockwise direction as viewed in Fig. 1, ²⁵ is adapted to engage within the openings between the teeth of the ratchet wheel. When the parts are in static condition, clockwise movement of the pawl 20 is prevented by its engagement with the nose of arm 26 ³⁰ which at this time is located between a latch 28 and a projecting portion 30 of the member 22.

The type cylinder 32 is journalled on the shaft 17 but during operative condition of ³⁵ the mechanism is constrained to rotate therewith by reason of the fact that a slide 34 adjustable radially in member 22 by a screw 36 carries a hook 38 embracing a pin 40 between rubber shock absorbers 42, the pin ⁴⁰ and shock absorbers being carried by the type cylinder. From Fig. 2 it will be clear that turning of the screw 36, which is rotatably mounted in member 22 and held ⁴⁵ against radial movement, will serve to move slide 34 radially so that its hook may be disengaged from the pin. As a result the type drum may be rotated on the shaft independently of other parts of the mechanism.

Members 44 carried by the periphery of ⁵⁰ the cylinder provide dovetailed openings for the reception of replaceable type plates 46 which may be placed in position between side flanges 48 and then clamped by the members.

The type cylinder carries a cam drum ⁵⁵ about which are located cams 52 staggered axially and angularly disposed to correspond with the type plates 46. At the ends of the series of cams 52 are transverse cams ⁶⁰ 54 and 56 having axial extents as great as that of the entire series of cams 52, the cams 54 and 56 corresponding angularly respectively to the numbering head 58 and the dating head 60.

The numbering head 58 is adapted to be

actuated upon each operating revolution of the type cylinder so as to successively number the tickets, this being effected by the oscillation of arm 62 by the eccentric strap 64 surrounding the eccentric 66 journalled ⁷⁰ on shaft 17 and arranged to be normally held stationary by the engagement of an arm 68, pivoted thereto, with a pin 72 fixed to the casing, the arm being releasably held on the pin by a spring detent. A pin ⁷⁵ 70 similar to pin 72 and also associated with a spring detent is carried by the cam drum. If it is desired to turn the type cylinder for cleaning or replacement of type plates, the arm 68 may be released from pin 72 and engaged with pin 70 so that the eccentric and type cylinder will turn as a unit, without, therefore, causing actuation of the numbering head.

An inker 74 is provided consisting of a ⁸⁰ well, an inking roller 76, and suitable transfer rollers carrying ink from the well for application to the inking roller. The inking roller is mounted on an axle and is movable upwardly into engagement with the type ⁹⁰ surfaces on the type cylinder by arms 78, slots in which receive the ends of the axle. The arms 78 are carried by a transverse shaft 79 which also carries an arm 80 supporting at its outer end a pin 82 on which ⁹⁵ slides a roller cam follower 84, the function of which will be hereafter described. A spring 86 urges the arm 80 in a counterclockwise direction as viewed in Fig. 1, normally ¹⁰⁰ maintaining the roller 76 in lowered position engaging the intermediate transfer roller and out of the path of the type surfaces. To insure proper distribution of ink the intermediate roller is driven through suitable gearing by the rotation of an arm ¹⁰⁵ 88 by engagement with a pin 90 carried by gear 12. The inker is mounted on a track 92 up which it may be slid by an operator into its active position being held therein by a suitable releasable latch. This inker ¹¹⁰ is of the same general type disclosed in the Webb applications referred to above or illustrated in the application of Horace D. Black, Serial Number 359,889, filed May 2, ¹¹⁵ 1929.

In order to produce a positive, accurate feed of the ticket strip a feed wheel 96 is provided, the wheel carrying pins 98 for engaging within perforations in the ticket strip and thereby advancing it along the stationary guide 120. The pin wheel 96 is secured to a shaft carrying a pinion 100 meshing with a gear 102 which carries a ratchet wheel 104 and a second holding ratchet wheel ¹²⁰ 106. A pawl 108 adapted to engage the teeth of the ratchet wheel 104 is secured to shaft 17. A lever 110 pivoted to the frame is provided at one end with a follower engaging a cam 112 on the shaft 17, and at its other end with a detent nose 114 adapted ¹²⁵ 130

to engage within the spaces between the teeth of wheel 106. The follower of lever 110 is held in engagement with the cam 112 by a spring 116 which acts on a bar 118 pivoted to a downwardly extending arm of the lever and passing through plate 6 where it terminates in a button which may be pressed by an operator to free detent 114 from wheel 106 and thereby permit the pin wheel to be freely rotated. This is of advantage when a new strip is to be inserted into the guide 120 since the wheel may then turn to properly engage a pin thereof into a hole in the strip. Upon release of the bar 110, the strip is manually moved until the detent snaps between a pair of teeth, thereby insuring the initial position of the strip so that it is properly located for a subsequent issuing operation.

20 A pivoted knife 122 cooperates with a suitable fixed ledger blade to sever the strip. This knife, which is of the form illustrated in Fig. 4 so that it cuts the strip both ways from the hole outwardly, is engaged by a pivoted lever 123 connected by a link to a bell crank 124. A spring 125 normally holds the bell crank to maintain the knife retracted to permit the free passage of the ticket strip, the knife being moved for a cutting movement by engagement of pawl 108 with the forwardly extending arm of the bell crank. It is to be noted that the pawl 108 thus serves for a double function, its normal position being as shown in Fig. 3 from which it will be obvious that it moves the pin wheel at the end of a cycle and operates the knife at the beginning of a succeeding cycle.

40 Pivotedly mounted on a transverse rod fixed in the frame is a member 126 carrying a continuation of the strip guide above the knife and an impression roller 128 adapted to press the ticket being printed against the type surfaces at the proper times. A curved guide 130 carried by 126 presents the ticket to the ejecting roller 132 driven by the overrun of the motor by a flexible spring belt connection to a pulley carried by gear 12. The ejecting roller is carried on a cross shaft 135 and serves to discharge the ticket through a slot in the cover plate 4.

50 The downwardly extending arm of member 126 carries a pin 136 on which is slidably mounted a roller 138. A spring 140 urges the member 126 in such direction as to bring roller 128 into engagement with stop 141 and to maintain the roller 138 in position to be engaged by cams 54 and 56 and also by one of the cams 52, the particular cam 52 depending upon the position of the roller on the pin 136. The roller is moved along the pin by its engagement in one bifurcated end of spring element 142, the opposite end of which similarly engages the roller 84. As illustrated best in Fig. 4

the element 142 is carried by a slide 144, guided for movement transversely of the machine and carrying a pin 146 engaged by the forked end of lever 148. This lever is normally urged in a clockwise direction, as viewed in plan, by a spring 150, being thus held in engagement with the end of a lever 152 connected to stirrup 154 journalled on a transverse shaft 156 and having a sloping upper edge 157 (Fig. 5) engageable by arms 158 also loosely mounted on shaft 156 and held up by springs 159. A key 160 is pivoted to each arm and projects upwardly through the top of the casing so as to be manually depressible by an operator.

55 The mechanism associated with the keys is best illustrated in Figs. 3 and 7, to which reference may now be made. Extending across the machine is a fixed bar 161 adapted to be engaged by hook members 162 one of which is pivoted to each key lever 150. (The members 162 associated with the key levers illustrated in Figs. 1 and 7 are omitted for clearness.) The hook members are so arranged that when the keys are sufficiently depressed to operate the mechanism they will engage the bar 161, being moved rearwardly by suitable springs, and prevent rise of the key until the end of the cycle of operation.

60 Journalled on the shaft 156, which is pivoted in the side walls of the casing, is a stirrup 163 acted upon by a spring 165 and extending beneath all of the key levers so that as they are rocked by depression of their keys the stirrup will be rocked in a counter-clockwise direction, as viewed in Figs. 3 and 7. Carried by the ends of shaft 156 are downwardly extending arms 164 and 164' to which is pivoted a clearing stirrup 166 held in normal engagement with bar 161 and just forward of, or aligned with, its forward edge by springs 168 and 168' which also serve to urge shaft 156 in a counter-clockwise direction. When the shaft is free to so move, its motion is limited by engagement of the arm 164 with stop 170. Also pivoted to arm 164 and controlled by a spring 171 is a latch 172 having a nose 174 which, when the machine is not operating, engages a block 176 fixed to the casing, thereby holding shaft 156 and its associated parts against the action of spring 168.

65 A tripping member 178 is pivoted to the stirrup 163 and depends therefrom, being held in engagement with latch 172 by a spring 190, engagement taking place below a ledge 180 formed on its rearward edge. Pivoted on the member 178 is an element 182 provided with an end 184 overlapping the ledge 180 and extending somewhat below it when the element is held in contact with a stop 188 on the member 178 by a spring 186. The nose 174 of the latch is of sufficient lateral thickness to engage both 178 and 182.

It will be noted that the arm 26 is secured to shaft 156 as is also an arm 192 engageable by a cam 194 carried by the shaft 17. In résumé, the elements 26, 192, 164, and 164' are fixed to the shaft; elements 152, 154, 158 and 163 and switch blade 204 are pivoted thereon for movements relatively thereto. The switch blade 204 is arranged to close the motor circuit by bridging contacts 206, being associated with elements hereafter described.

As in the machine illustrated in the applications referred to above, members 196 are utilized to prevent the simultaneous depression of two or more keys.

To prevent operation of the machine upon failure of the supply of strip S, a feeler 200 is provided arranged to drop when the end of a strip passes beneath it over roller 198 and permit an arm 202 to move into the path of stirrup 163 and prevent its depression.

Records of the number of each kind of tickets issued and also the total number are kept on suitable counters operated in the following manner. An eccentric strap 208 embraces an eccentric 210 secured to the shaft 17. This strap is pivoted at its free end to the stirrup carried by the oscillatory shaft 213, which supports a pin 217 on which are pivoted a number of levers 216, one corresponding to each key. Springs 214 normally hold these levers so that pins carried by their ends engage within the outer ends of slots in the operating levers 218 of the individual counters 220. When in this condition, even though the stirrup 212 is rocked during each revolution of the main shaft, the angular movements of arms 218 are insufficient to operate the counters. On the other hand when the levers 216 are depressed by pins 222 on the key bars, the pins move to the inner portions of the slots so that the same movements of stirrup 212 will produce greater angular movements of the arms 218 sufficient to actuate the counters.

An arm 226 carried by shaft 213 is linked connected to the operating lever of the total counter 224 which is thus operated upon each revolution of the main shaft.

The parts associated with the switch blade 204 will be clear from Fig. 8. As previously stated, the blade is pivoted on the shaft 156 through the medium of the insulating arm 300. A spring 302 reacting between the arm 300 and stirrup 166 urges the arm forwardly against a stop member 304 carried by the arm 164' and extending laterally. By reason of this connection the switch blade will normally move in unison with the arm 164' and may, so far as the ordinary cycle of operation is concerned, be considered as integral therewith. The switch blade is, however, movable to close the motor circuit independently of the arm 164' by depression of an extra key 306 adapted

to rock a lever 308 pivoted on shaft 156 and carrying an element 310 arranged to contact with the arm 300. Obviously if the circuit is closed by depression of key 306, the release of the key will effect opening of the circuit since the blade will be moved to normal position by spring 302.

The preceding description of the machine will make clear the operations of the several groups of elements. There will now be described the general operation of the machine with particular reference to the relative timing of the operating parts and those functions of certain parts which are not obvious upon casual inspection.

In all of the various figures the parts are illustrated in those positions which are assumed when the machine is prepared to issue a ticket upon the depression of a key by an operator. Upon the normal down-stroke of any key, various events occur in such rapid succession as to occur almost simultaneously. The key lever 158 engages the stirrup 163 rocking it about the shaft 156 and thereby causing 178 to move downwardly. As this occurs end 184 of member 182 engages nose 174 of latch 172 and yields upwardly against the tension of the light spring 186, which is insufficient to disengage the latch, until the ledge 180 engages the latch moving it until its nose clears block 176. At this time the action of the selecting mechanism has been completed, the arm 158 having engaged the sloping edge 157 of stirrup 154 and having thereby moved the forked member 142 to carry rollers 84 and 136 into the path of the cam 52 corresponding to the depressed key. The selection is effected by the degree of movement of the lever 158 following its engagement with stirrup 154. Since the strokes of the levers are the same but their contacts with the stirrup are delayed for varying periods due to sloping edge 157, it is obvious that the movement of the stirrup and therefore those of the cam following rollers will be variable depending on the key selected.

As soon as the nose 174 is disengaged from block 176, the spring 168 acts to rock shaft 156 producing the simultaneous occurrence of several operations. The clearing stirrup 163 moves rearwardly below bar 161 permitting the hook 162 carried by the depressed lever 158 to swing so as to engage the under side of the bar whereby the key is prevented from rising until the end of the cycle and the cam following rollers 84 and 138 are retained in their adjusted positions.

As the nose 174 moves beneath the block 176, the member 182 drops into engagement with the stop 188 whereby its end 184 will lie below the under surface of the block. The usefulness of this action will be brought out later and is here mentioned only because

of its occurrence in the sequence of operations now under discussion.

When the shaft rocks, member 26 is disengaged from lever 20 and also from the ledge 30 on member 22. The shaft 17 is thus freed to rotate and pawl 18 will engage between the teeth of member 16. The type cylinder is unbalanced so that it will tend of its own weight to rotate in the direction of the arrow in Fig. 1. Since the gear 14 will generally stop so that no opening of the wheel 16 is opposite the pawl 18, there will generally occur some angular movement of the type cylinder and shaft 17 prior to the time when pawl 18 engages. When the shaft 156 rocks it also closes the circuit through the driving motor which of course requires some small interval to gain speed. However the shaft 17 is already moving when it is picked up by the motor, and its unbalanced condition aids the motor, so that full motor speed is attained in a minimum of time and maintained through the cycle with a resultant considerable reduction in the time required for the completion of a ticket issuing operation as compared with the time which would be required if the design were such that the motor was obliged to start under load.

By the movement of shaft 156, the arm 192 is located in position for later engagement by cam 144.

Owing to the various events just described, the type cylinder is set into operation for the issuance of a ticket. Up to this time the knife 122 has remained retracted and above its path there projects a length of ticket strip equal to that of the desired ticket, one of the perforations in the strip lying directly in the path of the knife. The cam 108 (Fig. 3) momentarily engages and then disengages the lever 124 producing a cutting movement of the knife to sever a ticket followed by its retraction by spring 125 to inactive position clearing the path of feed of the strip.

At approximately the time severing takes place, the cam 54 will engage the roller 84 thereby raising inking roller 76 into engagement with the moving type on the numbering head 58 to freshly ink the same. As soon as the numbering head passes the inker, the roller 84 drops off the cam whereupon roller 76 again drops to receive further ink from the transfer roller.

Rotation now continues bringing the numbering head opposite the impression roller 128. When this position is approached, the cam 54 will engage roller 138 throwing the impression roller forwardly to press the ticket against the numbering head so that printing takes place, the ticket being fed a determined distance by the type on the head.

The roller 138 will ride off cam 54 immedi-

ately after this event so that spring 140 may retract the impression roller.

The cam 54 extends laterally so as to engage the rollers 84 and 138 in all their possible positions of adjustment and accordingly 70 numbering of every issued ticket occurs. On the other hand these rollers are engaged by only one of the cams 54 so that inking of and printing by only one of the plates 46 will occur in any cycle, the plate being determined by the selected position of the rollers. The inking and printing by the chosen plate take place in the same fashions as described above in connection with the numbering head so that these operations need not be 80 repeated. The ticket is fed, of course, a relatively greater distance.

A similar series of events occur in connection with the dating head 60, the corresponding cam being 56 which, like 54, engages the following rollers in all positions so that every ticket is dated. The feed in this case is sufficient to carry the ticket into engagement with ejection roller 132 which, being driven by the overrun of the motor, serves 90 to snap the ticket out through the slot in the cover plate.

As the end of the cycle approaches, the cam 112 acts on lever 110 causing it to free the wheels 106 and 104 and gear 102 which move as a unit. Immediately thereafter the pawl 108 engages a tooth of ratchet wheel 104 moving it to thereby feed the strip the length of one ticket. The lever 110 is released prior to the end of the desired movement of the wheels so that its nose may snap into a notch holding the wheels, and thereby the pin wheel 96, in a definite position. This position is defined by the location of a hole in the strip in alignment with the 105 knife.

After this feeding action takes place cam 144 engages arm 192 thereby rocking shaft 156 in a clockwise direction as viewed in Figs. 3 and 7. The switch is thereby opened cutting off the supply of current to the motor. The inertia of the parts, however, produces a completion of the cycle. As the shaft rocks, the nose of member 26 is brought into the path of latch 28, lever 20 and ledge 30. It first cams the latch inwardly, is then engaged by the lever 20 to thereby disengage the clutch, and is last engaged by the ledge 30 to positively stop the type cylinder. The latch 28 then snaps beneath it to prevent 115 rebound and also to assist in maintaining the type cylinder against rotation in either direction.

It is to be noted than when the machine finally approaches its position of rest the cam 194 disengages lever 192. However reversal of movement of shaft 156 is prevented by the latching of nose 174 with block 176, so that the member 26 will retain the position it has assumed.

If the operator has relieved the depressed key of pressure, it will rise under the action of its spring 159 as soon as the stirrup 166 clears the hook 162 from bar 161. On the other hand, even though the operator does 5 continue to press the key, the machine will not be kept from stopping. In such case, the nose 174 engages end 184 of member 182 rocking element 178 outwardly against the tension of spring 190. Furthermore the machine 10 cannot again be set into operation unless the key is permitted to rise sufficiently so that the end 184 is above the nose 174 thereby permitting element 178 to again swing inwardly. The parts are so designed 15 that extensive movement of the keys must take place thereby preventing the accidental issue of more than one ticket.

As the key rises, stirrup 154 is disengaged so that the rollers 84 and 138 may be returned to their initial positions by spring 20 150.

During the rotation of shaft 17, and subsequent to its printing operation, the numbering head 58 is advanced one unit by the 25 travel of strap 64 about the cam 66 which is held stationary by engagement of arm 68 with the fixed pin 72. The counter 224 and that counter 220 corresponding to the 30 depressed key are also actuated during the cycle by the rocking of stirrup 212 by eccentric 210.

Since the discharge roller 132 is operated directly by the motor, if it should fail for 35 any reason to eject a ticket at the end of a cycle it may be rotated by depression of key 306 whereupon the motor will operate without effecting rotation of the type cylinder or otherwise disturbing any of the control elements from their static positions. 40 This independent operation of the motor is also useful in that the inking rollers may be rotated prior to operation of the machine after a period of activity to thereby insure proper distribution of ink for the printing 45 of the first ticket. The key 306 may also be used as a testing key to determine whether the motor is operating properly.

The accomplishment of the various objects set forth above will be clear from the foregoing description. It will be apparent to those skilled in the art that numerous variations in details of the invention may be made without departure from the spirit 55 thereof as defined in the following claims.

What I claim and desire to protect by Letters Patent is:

1. In a ticket printing and issuing machine, a rotatable type member provided 60 with a series of successively arranged printing elements, means for presenting to the type member a ticket to be printed, driving means for the type member, a plurality of keys, and mechanism controlled by actuation 65 of a key to effect rotation of the type mem-

ber by the driving means and printing of the ticket by a selected printing element, said mechanism including devices limiting the type member to a single rotation upon each actuation of a key, which devices include a stop, a latch engageable with the stop to maintain parts of the machine in inoperative position, an element actuated upon depression of a key to trip the latch, and means for restoring the latch at the 70 end of a cycle of operation, said element yielding if engaged by the restored latch whereby it does not prevent engagement of the latch with the stop. 75

2. In a ticket printing and issuing machine, a rotatable type member provided with a series of successively arranged printing elements, means for presenting to the type member a ticket to be printed, driving means for the type member, a plurality of keys, and mechanism controlled by actuation of a key to effect rotation of the type member by the driving means and printing of the ticket by a selected printing element, said mechanism including devices 80 limiting the type member to a single rotation upon each actuation of a key, which devices include a stop, a latch engageable with the stop to maintain parts of the machine in inoperative position, an element actuated upon depression of a key to trip the latch, and means for restoring the latch at the 85 end of a cycle of operation, said element yielding if engaged by the restored latch whereby it does not prevent engagement of the latch with the stop. 90

3. In a ticket printing and issuing machine, a rotatable type member provided with a series of successively arranged printing elements, means for presenting to the type member a ticket to be printed, driving means for the type member, a plurality of keys, and mechanism controlled by actuation 100 of a key to effect rotation of the type member by the driving means and printing of the ticket by a selected printing element, said mechanism including devices 105 limiting the type member to a single rotation upon each actuation of a key, which devices include a stop, a latch engageable with the stop to maintain parts of the machine in inoperative position, an element actuated upon depression of a key to trip the latch, and means for restoring the latch at the 110 end of a cycle of operation, said element yielding if engaged by the restored latch whereby it does not prevent engagement of the latch with the stop, and whereby release and subsequent depression of a key is necessary to again trip the latch. 115

4. In a ticket printing and issuing machine, a rotatable type member provided with a series of successively arranged printing elements, means for presenting to the type member a ticket to be printed including a guide for a strip, a pin wheel for intermittently feeding the strip along the guide, and ratchet devices for moving the pin 120 125 130

wheel upon rotation of the type member, and key controlled driving means for the type member.

5. In a ticket printing and issuing machine, a rotatable type member provided with a series of successively arranged printing elements, means for presenting to the type member a ticket to be printed including a guide for a strip, a pin wheel for intermittently feeding the strip along the guide, ratchet devices for moving the pin wheel upon rotation of the type member, means for preventing overthrow of the pin wheel after each movement, and key controlled driving means for the type member.

6. In a ticket printing and issuing machine, a rotatable type member provided with a series of successively arranged printing elements, means for presenting to the type member a ticket to be printed including a guide for a strip, a pin wheel for intermittently feeding the strip along the guide, ratchet devices for moving the pin wheel upon rotation of the type member, means for preventing overthrow of the pin wheel after each movement, said means including a retaining pawl, and key controlled driving means for the type member.

7. In a ticket printing and issuing machine, a rotatable type member provided with a series of successively arranged printing elements, means for presenting to the type member a ticket to be printed including a guide for a strip, a pin wheel for intermittently feeding the strip along the guide, ratchet devices for moving the pin wheel upon rotation of the type member, means for preventing overthrow of the pin wheel after each movement, said means including a retaining pawl, manually controlled means for rendering the retaining pawl inoperative whereby the pin wheel may freely move during insertion of a strip, and key controlled driving means for the type member.

8. In a ticket printing and issuing machine, a rotatable type member provided with a series of successively arranged printing elements, means for presenting to the type member a ticket to be printed including a guide for a strip, a pin wheel for intermittently feeding the strip along the guide, a pawl rotatable with the type member, a ratchet wheel having teeth engageable by the pawl and arranged to drive the pin wheel, a knife adapted to sever the strip, means engageable by the pawl to operate the knife, and key controlled driving means for the type member.

9. In a ticket printing and issuing machine, a rotatable type member provided with a series of successively arranged printing elements, driving means, an element arranged to be driven by the driving means in the cyclical operation of the machine, and

releasable connections between the type member and element, whereby, upon release of the connections, the former may be rotated independently of the latter, said connections being operable by manipulation of an accessible, radially extending screw, and including spaced members carried by the type member and an element radially movable by manipulation of the screw either between said members or out of engagement therewith.

10. In a ticket printing and issuing machine, a rotatable type member provided with a series of successively arranged printing elements including a numbering head, means for actuating the numbering head including an eccentric strap connected thereto and surrounding a normally fixed eccentric, driving means, an element arranged to be driven by the driving means in the cyclical operation of the machine, releasable connections between the type member and element, whereby, upon release of the connections the former may be rotated independently of the latter, and means whereby the eccentric may be connected to the type member to rotate therewith whereby relative motion between the eccentric and strap is prevented and the numbering head is not actuated.

11. In a ticket printing and issuing machine, a rotatable type member provided with a series of successively arranged printing elements including a numbering head, means for actuating the numbering head including an eccentric strap connected thereto and surrounding a normally fixed eccentric, and means whereby the eccentric may be connected to the type member to rotate therewith whereby relative motion between the eccentric and strap is prevented and the numbering head is not actuated.

12. In a ticket printing and issuing machine, a rotatable type member provided with a series of successively arranged printing elements, means for presenting to the type member a ticket to be printed, a driving motor, a switch controlling the motor circuit, and a key controlled means for closing the switch and effecting rotation of the type member by the motor and printing of the ticket by a selected printing element, said switch being closable independently of the key controlled means to operate the motor without effecting rotation of the type member.

13. In a ticket printing and issuing machine, a rotatable type member provided with a series of successively arranged printing elements, means for presenting to the type member a ticket to be printed, a driving motor, a switch controlling the motor circuit, key controlled means for closing the switch and effecting rotation of the type member by the motor and printing of the ticket by a selected printing element, and

means for ejecting a printed ticket driven by the motor through connections independent of the type member, said switch being closable independently of the key controlled means to operate the motor and ejecting means without effecting rotation of the type member.

14. In a ticket printing and issuing machine, a rotatable type member provided with a series of successively arranged printing elements, means for presenting to the type member a ticket to be printed, a driving motor, a switch controlling the motor circuit, key controlled means for closing the switch and effecting rotation of the type member by the motor and printing of the ticket by a selected printing element, and an inker having an inking roll arranged to receive ink from a supply and apply it to the printing elements, said roll being driven by the motor through connections independent of the type member, and said switch being closable independently of the key controlled means to operate the motor and inking roll without effecting rotation of the type member.

15. In a ticket printing and issuing machine, a rotatable type member provided with a series of successively arranged printing elements, means for presenting to the type member a ticket to be printed, a driving motor, key controlled means for closing the motor circuit and effecting rotation of the type member by the motor and printing of the ticket by a selected printing element, and an inker having an inking roll arranged to receive ink from a supply and apply it to the printing elements, said roll being driven by the motor through connections independent of the type member, and the motor circuit being closable independently of the key controlled means to operate the motor and inking roll without effecting rotation of the type member.

45 In testimony of which invention, I have hereunto set my hand, at Philadelphia, Pa., on this 3rd day of February, 1931.

HENRY A. THOMSON.
